[57] CLAIM

The ornamental design for a motorcycle timer cover, as shown and described.

DESCRIPTION

FIG. 1 is a perspective view of an ornamental design of a motorcycle timer cover according to our invention; FIG. 2 is a top view thereof;

FIG. 3 is a front elevational view thereof, the rear elevation view being a mirror image thereof;

FIG. 4 is a right side elevation view thereof, the left side elevation view being a mirror image thereof;

FIG. 5 is a bottom view thereof;

FIG. 6 is a front perspective view of a motorcycle timer cover showing a second embodiment of our new design;

FIG. 7 is a top view of the embodiment of FIG. 6;

FIG. 8 is a right side elevation view of the embodiment of FIG. 6, the left side elevation view being a mirror image thereof;

FIG. 9 is a front elevation view of the embodiment of FIG. 6, the rear elevation view being a mirror image thereof; and,

FIG. 10 is a bottom view of the embodiment of FIG. 6.
